UNITED STATES PATENT OFFICE.

JOSE M. AIZPURA, OF TAMPA, FLORIDA.

FIREPLACE HEATER.

Application filed February 4, 1922. Serial No. 534,179.

To all whom it may concern:

Be it known that I, JOSE M. AIZPURA, a citizen of the United States, residing at Tampa, in the county of Hillsborough and 5 State of Florida, have invented a new and useful Fireplace Heater, of which the following is a specification.

This invention relates to a heater designed primarily for use within open fireplaces, one 10 of the objects of the invention being to provide a simple, durable and compact structure which can be set up readily within a fireplace and which delivers the products of combustion directly to the chimney but 15 provides an air chamber through which air can circulate from and to the room being heated, thereby to prevent the loss of heat which ordinarily occurs through the escape of heated air up the chimney of an open fireplace 20 instead of back into the room from which it was taken.

Another object is to provide a heater of this character having means for supplying moisture to the heated air, the moisture holding 25 means being accessible readily.

Another object is to provide the heater with a protecting screen so as to prevent injury to persons in close proximity to the heater.

30 With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

40 In the accompanying drawings the preferred form of the invention has been shown.

In said drawings—

Figure 1 is a front elevation of the heater.

Figure 2 is a section on line 2—2, Figure 45 1.

Figure 3 is a section on line 3—3, Figure 1.

Figure 4 is a section on line 4—4, Figure 3.

50 Figure 5 is a front elevation of a portion of the removable bottom door of the heater.

Figure 6 is a section on line 6—6, Figure 5.

Referring to the figures by characters of 55 reference 1 designates the back wall and 2

the side walls of the inner casing or stove portion of the furnace, these walls 60 upstanding from a solid bottom 3. The front of the inner casing is open from the top to the bottom thereof except for narrow side flanges 4 extending throughout the height of the open front. The top of the inner casing has its walls converging upwardly as shown at 5 from the four sides of the inner casing and they merge into a thimble 65 6 upstanding from the top. A flat baffle plate 7 is extended from front to rear of the inner casing and is attached to the front and rear walls at a point above the open front. This baffle is spaced from the 70 side walls and is provided to prevent products of combustion from flowing to the outlet thimble 6 on a straight line.

Secured along the top, sides and bottom 75 of the opening in the front of the inner casing are flanges 8 extending backwardly from the edges of an opening in the front wall 9 of an outer casing. The top portion of the wall 9 is foraminous as shown at 10 and the lower portions of the sides of the 80 wall 9 are likewise foraminous as shown at 11. The remaining portions of the wall 9 can be solid and if desired a water container 12 can be extended from the back face of 85 each side portion of the wall 9 above the foraminous portion 11. An opening 13 is formed within wall 9 directly above the front portion of each water container so that water can be directed readily through the opening into the container in rear 90 thereof.

Secured to the lower portions of the flanges 4, upon the front faces thereof, are brackets 14 and these brackets are adapted to be engaged by ears 15 extending laterally 95 from the sides of a bottom panel 16 constituting the lower door of the heater. This door or panel can be provided with draft openings 17 and a damper 18 can be slidably mounted on the back face of the door 100 or panel. This damper is preferably provided with a knob 19 slidable in a slot 20. The door or panel 16 is placed in position by lowering the arms 15 into engagement with the brackets. By shifting the damper 105 18 the draft through the heater can be regulated.

A door 21 is hingedly connected to one of the flanges 4 and is adapted to swing 110 against the opposed flange 4 so as to com-

pletely close the open front of the heater. This door is provided with a suitable latch 22 for fastening it in position when shut.

A fire pot 23 which can be in the form 5 of a basket mounted on suitable legs 24 is removably mounted on the bottom 3 back of the door or panel 16.

Holding ears 25 are extended from the outer edges of the flanges 8 and are supported 10 in substantially the same plane with the wall 9. These ears are adapted to be detachably engaged by downwardly extending brackets 26 extending backwardly from the side portions of a foraminous panel 27 adapted to fit between the flanges 8 and 15 against the ears 25. The panel is slightly shorter than the distance between the bottom of the heater and the top flange 8, as shown in Figure 3. Thus it will be apparent 20 that the panel 27 can be slid upwardly to disengage brackets 26 from ears 25 and allow the removal thereof from the heater in order to give access to the doors 21 and 16.

The inner casing of the heater is adapted 25 to be partly housed within an outer casing 28 which is closed at the sides, back and top and has an opening 29 in its top to receive the thimble 6. The wall 9 forms the front of the casing 28. An air chamber 30 is provided 30 between the inner and outer casings, this chamber communicating with the external atmosphere through the foraminous portions or gratings 10 and 11.

Secured to the sides of the outer casing 35 and extending inwardly so as to abut against the inner casing 1 are baffles 31 which are extended rearwardly from the front portion of the outer casing and are extended upwardly short distances between the sides of 40 the inner and outer casing as shown at 32. The front ends of these baffles are adapted to contact with the solid portions of the wall 9 between the lower gratings or foraminous portions 11 and the water containers 12.

For the purpose of holding the casing 28 firmly in position relative to the inner casing, a bottom plate 33 is preferably extended inwardly from the back wall of the outer 50 casing and under the bottom of the inner casing.

It is to be understood that after the parts 55 of the structure have been properly assembled, the entire structure can be moved back into an open fireplace so that the hot products of combustion will flow from the thimble 6 into the chimney flue. By removing panel 27 the door 21 can be opened.

and a fire can be built on the fire pot 23. The door can then be closed, the damper 18 regulated, and the screen panel 27 replaced. The hot products of combustion will heat the inner casing to a high temperature and the air contained within the chamber 30 will thus be heated and flow upwardly around the 65 baffles 31 and their extensions 32. The circulation thus set up will cause cold air to flow from the room being heated, through the gratings or foraminous portions 11, into chamber 30, and thence upwardly and outwardly through the grating 10. By placing water within the holders 12 moisture will be supplied to the air being heated.

By removing the panel 27 and opening the door 21 the door or panel 16 can be 70 lifted and removed and the fire pot readily taken out of the inner casing.

It has been found in practice that a structure such as described is advantageous because of its simplicity, the ease with which 75 it can be installed and its efficiency as a heating medium.

What is claimed is:—

A heater for open fireplaces comprising an outer casing having a front wall formed with 85 an opening, said wall having foraminous portions adjacent the lower portions of the sides of the opening and a foraminous portion extending transversely of the top of the wall, an inner casing within the outer 90 casing and spaced therefrom, said inner casing having a smoke outlet, flanges extending inwardly from the edges of the opening in the front wall of the outer casing and secured to the front wall of the inner 95 casing, a foraminous closure insertible downwardly within the opening in the front wall, cooperating means upon the closure and the flanges and back of the closure so as to be concealed thereby, for holding the closure 100 in position when moved downwardly within the opening, baffles extending backwardly from the front wall of the outer casing and between the side walls of the inner and outer casing, said baffles having their rear 105 ends extended upwardly and being located above the foraminous portions at opposite sides of the opening in the front wall.

In testimony that I claim the foregoing as my own, I have hereto affixed my signature in the presence of two witnesses.

JOSE M. AIZPURU.
